(57) **CLAIM**

The ornamental design for an oven door protector, as shown and described.

DESCRIPTION

FIG. 1 is a perspective view of an oven door protector showing my new design;

FIG. 2 is a right-side view thereof;

FIG. 3 is a left-side view thereof;

FIG. 4 is a top view thereof;

FIG. 5 is a bottom view thereof;

FIG. 6 is a front view thereof;

FIG. 7 is a back view thereof;

FIG. 8 is an enlarged perspective view of the portion of the oven door protector shown in FIG. 1;

FIG. 9 is an enlarged top view of the portion of the oven door protector shown in FIG. 4;

FIG. 10 is an enlarged bottom view of the portion of the oven door protector shown in FIG. 5;

FIG. 11 is a perspective view of the oven door protector in an alternate configuration; and,

FIG. 12 is an enlarged perspective view of the portion of the oven door protector shown in FIG. 11.

The broken lines in the drawings depict portions of the oven door protector that form no part of the claimed design.
